UNITED STATES PATENT OFFICE

PAUL DOUGLAS TYERS, OF WATFORD, ENGLAND, ASSIGNOR TO IGRANIC ELECTRIC COMPANY LIMITED, OF LONDON, ENGLAND

ELECTRIC MICROPHONE

Application filed May 28, 1928, Serial No. 281,332, and in Great Britain June 2, 1927.

This invention relates to electric microphones and has for its object the provision of a microphone which shall have a fairly even response over a wide range of frequencies. A further feature of this invention is that a microphone may be constructed so as to be comparatively robust without departing from a good response characteristic over a wide range. The well known carbon compression effect is utilized for the microphonic property of the microphone. A carbon microphone consists essentially of a conducting back plate, a layer of granules and a carbon diaphragm or the like. The response of such an instrument is very unequal and it is quite useless for accurate sound reproduction. Another type of carbon microphone which has an even response has been developed, and consists essentially of a layer of carbon granules, usually held in position by means of a sheet of rubber. The current path is along the length of the layer, that is, substantially at right angles to the normal direction of the sound waves. The carbon layer is provided with two conductors, usually in the form of carbon rods, at each end of the layer, connection being made to these rods. This type of microphone has been described in some detail in order that it may be clearly differentiated from the present invention.

The principle employed in the carbon microphone constructed according to this invention, is that of the usual type, in which the current path is substantially in the same plane as the sound waves. In other words the current passes between a diaphragm and a conducting back plate at right angles to the plane of the carbon layer.

According to this invention a microphone is constructed substantially as follows. The diaphragm is of a composite nature and consists of a conducting portion and a supporting portion. The conducting portion is a substantially uniform and even layer of extreme thinness of metal which does not oxidize easily, such as gold. This is attached to the supporting portion, which is an area of rubber or similar material, the thickness of which is preferably not more than one or two

millimetres. The metallicized diaphragm may be produced in several ways, but whatever method is adopted it falls into one of two processes, electrical deposition or cementing. When the metal is electrolytically deposited the rubber may be coated with carbon to render it sufficiently conductive for deposition to occur. The actual method of coating however, is not a feature of this invention and it may be accomplished by any means known to the art.

When the rubber or like material is metallicized by cementing certain methods are found necessary and these constitute features of this invention. The metal such as gold is beaten into the form of "leaf" in known manner and it is placed on a plane surface in an atmosphere free from heavy air currents. The rubber is then given a coating of adhesive and when it is tacky it is placed on the metal leaf which will then adhere firmly to it. It is a feature of this process that whatever adhesive may be used, the solvent has no appreciable action on the rubber or like material, and that the adhesive when dry may be of a flexible nature. It is also necessary to use the minimum quantity so that it has no appreciable effect upon the mechanical properties of the diaphragm. By way of example may be mentioned water soluble gums which when set remain flexible for considerable periods. Another method which may be used is that of spraying the rubber with atomized acetone or similar solvent containing a small amount of celluloid or cellulose acetate. It is a further feature of this invention that the coating operation be carried out when the rubber is attached to the supporting frame or like constituting part of the microphone. If this is not done, the metal layer may be broken when the rubber is fixed to its supporting frame which will be referred to hereinafter.

The diaphragm hereinbefore particularly described is attached to a frame or support either by clamping or by means of any suitable adhesive. It is important that the rubber is only slightly stretched, the stretching employed being that sufficient to remove any sagging when the frame is held vertically.

The remaining essential portion of the microphone consists of a housing with a conducting back and the granule layer contained therein. In order to remove as far as possible any inherent mechanical resonances in the microphone, it is advisable to make the granule housing in the form of a recess in a block of fairly non-resonant substance such as marble, but it is not desired to limit this invention to the use of this or like substance. If the housing is of non-conducting material such as marble it is necessary to render the granule recess conducting at the back, by inserting a carbon or metal plate. When the granule housing is of conducting material it is preferable to insulate the sides of the recess in any convenient manner in order to obtain a uniform current distribution through the carbon layer.

Connection is made to the diaphragm in the following manner. The front of the granule housing around the edge of the recess is coated with one or more layers of soft metal foil, such as lead or tin, the conducting edge thus formed being in intimate contact with a strip of somewhat thicker foil of any metal. The free end of this foil strip is then connected to a terminal. Another terminal is connected in any desired manner with the back conducting plate. When the granule housing is of conducting material the foil edge of the granule recess must, of course, be insulated from it, preferably by inserting an insulating gasket or washer. The prepared diaphragm attached to a frame is placed in front of the recess and the metallicized edge beds on to the soft foil, thereby establishing good contact with it. In order to introduce the granules, the recess is provided with a filling plug or the like. When the granule housing is of insulating material the terminals may be mounted directly upon it. When, however, the material is conductive the terminals must be insulated therefrom. The leads between the respective elements of the microphone and the terminals are taken through holes or tunnels suitably positioned in the granule housing. When the housing is conductive one terminal may if desired be connected directly to the housing.

When extreme purity in reproduction is desired it is necessary to eliminate every source of inherent mechanical resonance as far as possible and a feature of this invention lies in making the terminals of large diameter compared with their length and placing them as far as possible out of direct sound waves impinging upon the diaphragm. For example the terminals may be placed at the back of the granule housing or in suitable recesses at the sides of the housing, so that they are not subjected to direct sound waves.

In order to protect the diaphragm from mechanical injury the supporting frame may

be covered with gauze which may be either metallic or non-metallic. In the case of a microphone intended for great purity, the gauze is of muslin or like material free from natural resonances. The mechanical construction of the granule housing, recess, and diaphragm frame is not of great importance and does not form an essential feature of this invention and it may be modified without departing from the scope of the invention. The construction hereinbefore described is given as one convenient manner of carrying the invention into effect, and should be readily understood by those skilled in the art.

The dimensions of the granule recess and therefore the granule layer contained therein and the size of the granules are important factors determining the performance of the microphone, and the proportioning of these parameters in conjunction with the composite diaphragm hereinbefore described forms one of the essential features of this invention. The effect of the depth of layer and size of granule is well known. Briefly, however, the thicker the layer the less will be the total response to the high frequencies, the inverse also being true. It is also known that if the size of the granules is large there will be appreciable air space between them and therefore the absorption will vary at different frequencies. It is customary to obtain a substantially equal response over a desired frequency range by using a mixture of granules of various sizes and it will be obvious that similar frequency responses can be obtained by various sizes and mixtures of granules.

The robustness of a microphone constructed according to this invention depends largely upon the volume of granules employed, since the greater the volume the greater will be the head on the diaphragm, the term head being used in a hydrostatic sense. If this head is great, the granules will tend to pack and the microphone will be liable to go out of adjustment when subjected to strong mechanical shock. A feature of a microphone constructed according to this invention is that by using a small volume of granules and therefore a thin layer, comparative robustness can be obtained, and at the same time an even frequency characteristic can be obtained, by suitably adjusting the size and mixture of the granules according to known methods and practice. It will be obvious that when the layer is very thin, the ohmic resistance will be low and accordingly the microphone may be worked at fractional voltage if desired.

Another feature of this invention lies in the use of a plurality of microphones of the type described the microphone units being connected in any desired manner, preferably in series, the composite unit forming a micro-

phone of considerable sensitivity. When a composite microphone is employed, the various units may be so constructed that some, for example, respond especially to the higher frequencies, while others respond especially to the lower frequencies. In the case of a composite microphone the various granule layers and diaphragms may be mounted in one granule housing, or they may be provided with separate housings.

In order that this invention may be clearly understood several methods of applying its microphone construction are shown in the accompanying drawings. Figure 1, shows one form of suitable granule housing, while Figure 2, shows a cross section through such a housing with a diaphragm attached. Figure 3 shows the invention applied to another form of construction, while Figure 4, shows a composite microphone.

Referring to Figs. 1 and 2, the granule housing comprises a block of insulating material of the type described 1, provided with a recess 2, containing a conducting plate 3. The edge of the recess is coated with foil at 4, and holes 5 and 6 are provided for heavier foil leads to the foil edge 4, and the plate 3, respectively. A filling orifice 7 closed by a plug 8 communicates with the granule recess 2. The housing is provided with holes 9 adapted to take bolts or the like 11, for the purpose of retaining the diaphragm. Holes 10 are shown for the purpose of retaining bolts used to locate the plate 3, in the recess 2. The diaphragm 12, fixed to a frame 13, is protected by a gauze area 14, the whole being fixed in position by a frame ring 15, and the bolts 11. The leads and terminals are omitted for clearness and also the section lining of the housing in Fig. 2.

Figure 3, shows a more compact form in which the granule housing 16, is metallic and is provided with a granule recess 17, and an insulating gasket of the shape indicated 18. This is coated with metal foil 19 making contact with the diaphragm 20, attached to the frame 21. The diaphragm is protected by a gauze area 22 the whole being held in position by a frame ring 23, and bolts 24. A filling orifice is closed by a plug 26. Terminals are provided at 27 one being attached directly to the granule housing and the other to an insulating plate 28, held in position by bolts 29. A hole 30, is provided in the granule housing for a heavy foil or other lead between the appropriate terminal and the foil surface 19. The section lines on the granule housing are again omitted for clearness.

Figure 4, shows a composite microphone comprising a large granule housing 31, provided with a plurality of microphone elements 32. Terminals 34, are fixed to a plate of insulating material 33 carried at the back of the granule housing.

It is to be understood that this invention is not limited to any particular form of mechanical construction and those hereinbefore described are given only as methods of carrying the invention into effect. Both circular and square diaphragms have been shown, but other shapes may be used if desired. Similarly known methods of microphone construction may be used in conjunction with this invention without departing from its scope.

It is particularly not desired to limit this invention to specific sizes and mixtures of granules and thickness of layers as the method of adjusting them for any desired frequency response is well known to the art, and these factors are naturally determined by the particular purpose for which the microphone is required. A feature of this invention however, lies in the use of a very thin layer with suitably proportioned granules for the response desired, when the microphone is to be of a robust nature. Hitherto microphones have employed comparatively thin layers of the order of 3 millimetres, and when the area is appreciable the head is large. A thin layer according to this invention is intended to mean one of the order of less than 3 millimetres. It is clearly to be understood, however, that comparatively thick layers may be used in microphones constructed according to this invention.

What I claim and desire to secure by Letters Patent is:

1. An electric microphone comprising a quantity of conductive granular material, a diaphragm including a sheet of rubber and a thin metal layer intimately attached to one another, means for holding said granular material with a part thereof resting against the metal layer of said diaphragm and for supporting said diaphragm with the sheet of rubber directly exposed to the outer atmosphere and means for connecting the two arms of a circuit respectively to said metal layer and to a part of the granular material remote from said diaphragm whereby, as said diaphragm vibrates the electrical resistance between said two arms varies.

2. An electric microphone comprising a quantity of conductive granular material, a diaphragm including a sheet of rubber and a thin metal layer intimately attached to one another, an open ended housing of insulating material having its open end closed by means of said diaphragm with the metal layer inwards, whereby an enclosed space is constituted containing said granular material, a seating for said diaphragm of conductive material carried by said housing and means for connecting two arms of a circuit respectively to said seating and to a part of the granular material remote from the diaphragm.

3. An electric microphone comprising a

- quantity of conductive granular material, a diaphragm including a sheet of rubber and a thin metal layer intimately attached to one another, an open ended housing of insulating material having its open end closed by means of said diaphragm with the metal layer inwards and the rubber sheet directly exposed to the outer atmosphere so that an enclosed space is constituted containing said granular material, a seating for said diaphragm of conductive material carried by said housing and means for connecting the two arms of a circuit respectively to said seating and to a part of the granular material remote from the diaphragm.
4. An electric microphone comprising a quantity of conductive granular material, a diaphragm including a sheet of rubber and a thin metal layer intimately attached to one another, an open ended housing of insulating material having its open end closed by means of said diaphragm with the metal layer inwards, whereby an enclosed space is constituted containing said granular material said housing being so formed that said space is shallow in a sense at right angles to said diaphragm, a seating for said diaphragm of conductive material carried by said housing, a plate of conductive material located in said housing remote from said diaphragm and means for connecting the two arms of a circuit respectively to said seating and said plate.
5. An electric microphone comprising a quantity of conductive granular material, a diaphragm including a sheet of rubber and a thin metal layer intimately attached to one another, an open ended housing having its open end closed by means of said diaphragm with the metal layer inwards, whereby an enclosed space is constituted containing said granular material, said housing being so formed that said space is shallow in a sense at right angles to said diaphragm, a seating for said diaphragm of conductive material carried by said housing, a plate of conductive material located in said housing remote from said diaphragm, terminals connected respectively to said seating and said plate, said terminals being out of the direct path of the sound waves influencing said diaphragm and being of large diameter compared to their length.
6. An electric microphone comprising a quantity of conductive granular material, a diaphragm including a sheet of rubber and a thin metal layer intimately attached to one another, an open ended housing of insulating material having its open end closed by means of said diaphragm with the metal layer inwards, whereby an enclosed space is constituted containing said granular material, a seating for said diaphragm of conductive material carried by said housing, a plate of conductive material located in said hous-

ing remote from said diaphragm, means for connecting the two arms of a circuit respectively to said seating and said plate and a sheet of non-resonant gauze-like material located in front of said diaphragm.

In witness whereof I affix my signature.

PAUL DOUGLAS TYERS.
